[57] CLAIM

The ornamental design for an animal feeding dish, as shown and described.

DESCRIPTION

FIG. 1 is a top plan view of an animal feeding dish embodying my new design.

FIG. 2 is a bottom plan view thereof.

FIG. 3 is a side elevational view thereof, the other sides being the same as the side shown.

FIG. 4 is a sectional view taken along line 4—4 in FIG. 1.

FIG. 1

FIG. 3

FIG. 2

FIG. 4
